J. BERGMANN

CALCULATING MECHANISM

Filed Oct. 11, 1924

Patented Nov. 15, 1927.

1,649,379

UNITED STATES PATENT OFFICE.

JEAN BERGMANN, OF WANNEE, NEAR BERLIN, GERMANY.

CALCULATING MECHANISM.

Application filed October 11, 1924, Serial No. 743,120, and in Germany October 9, 1923.

This invention relates to calculating mechanisms, and particularly to those of the type in which a series of figure slides are adjusted by means of a stylus. Such a device is 5 shown in my Patent No. 1,567,564.

One object of the present invention is to provide control members in conjunction with the figure slides whereby the numbers set up will be indicated, and will also be set 10 up on a printing device.

Another object is to so arrange the control members that they will be operated by the stylus as it moves the figure slides and so 15 that they can also be moved independently of the figure slides, whereby the final result of a computation can be set up on the printing device.

One embodiment of my invention is shown 20 by way of example in the accompanying drawing, wherein

Fig. 1 is a plan view of the device with parts broken away for better disclosure of the underlying parts,

Fig. 2 is a cross section on the line 2—2 of 25 Fig. 1,

Fig. 3 is a detail view of a guide element which bears one of the figure slides

Fig. 4 is a cross section through the same,

Fig. 5 is a bottom view of one end of 30 said guide element, and

Fig. 6 is a vertical section on the line 6—6 of Fig. 1.

The machine comprises a series of figure 35 slides 1 corresponding to the number of places required for computation. The slides are mounted on guide elements *a* as indicated in Fig. 6, being secured thereto by means of hooks stamped out of the slides which engage in grooves *k* of the guides *a*. 40 The guides *a* are guided in slots *b* of an intermediate plate *c*.

Guides *a* have at their ends double T shaped heads *f*, each of which has two long transverse arms *g* and two short transverse 45 arms *h*. The short transverse arms are adapted to pass through lateral slots *d* of slots *b* when the guides are inserted in place. The long transverse arms *g* rest upon the intermediate plate and support the guide for sliding movement. The slots *d* are so positioned that the arms *h* do not register with them during the normal operation of the device.

50 The number slides are provided with a series of teeth 2 which form between them spaces 2' for the insertion of a stylus for

shifting the slides. A single series of numbers from 0 to 9 is arranged on each slide 1, the numbers being spaced in accordance with the spaces 2'. At the side of certain 60 of the spaces 2' are colored marks 3 for a purpose to be presently described.

Above each slide 1 is arranged a control slide 5 having apertures 6, which are wide enough to disclose the colored marks 3 on 65 slides 1. The control slides are provided with two series of numbers from 0 to 9, one above the other, as shown at the slide farthest to the right in Fig. 1.

Cover plates 7 and 7' are arranged over 70 the control and figure slides in such a way as to leave an open space through which the slides are operated. The results of the computation are read through holes 4 in plate 7' through which the numbers of the figure 75 slides are visible.

Upon a stationary transverse shaft 14' are rotatably mounted a number of type wheels 14 corresponding to the number of control slides 5. Each type wheel has secured to 80 it a gear 13 which is engaged by a toothed flange 12 of the corresponding control slide. A hood 14^a guards the type wheels. The type wheels are adapted to print on a record strip in a manner which will be described 85 later.

In the opposite ends of the casing in which the slides are mounted are a pair of transverse bars 8 and 9 adapted when moved toward each other to abut against the opposite 90 ends of the control slides to return to normal position any control slides which have been displaced. The bars 8 and 9 are moved toward each other by means of toggles 95 consisting of the bars 11. The bars 11 on each side are pivoted to each other at 10^a, while their outer ends are pivoted to the ends of the bars 8 and 9. By grasping the handles 10 secured to bars 11 and pulling outwardly 100 the toggles are broken and the bars 8 and 9 moved toward each other.

From the structure which has been described so far it will be seen that if a stylus is inserted in the hole opposite the numeral 4 of the second slide from the right and moved down until the stylus strikes against cover 7 the slides will assume the position in which they are shown in Fig. 1. The figure 4 of the number slide appears in the window 4, and the number 4 of the control slide appears just above the edge of the cover plate 7. The handles 10 are now pulled 110

outward and the control slide is returned to normal position by the bar 9. If a 2 is to be added to the 4 the stylus will be inserted in the hole of the control slide opposite the figure 2. The figure slide will thereby be moved down 2 spaces so that the number 6 will appear in the window 4 while the number 2 of the control slide will be seen just above the edge of plate 7. The 10 number added will therefore be indicated each time as a check upon the operation.

In order to transfer 1 to the next higher column when the number added gives a result greater than 9 the following structure 15 is provided:

A series of short axles n are mounted in a row across the intermediate plate c just below the lower edge of plate 7'. On the lower ends of the axles are small gears p 20 adapted to engage racks i of guides a . On the upper ends of the axles are mounted four toothed star wheels o . The gear engages the rack on the guide to the left of it while the tooth of the star wheel which extends to the 25 right lies under the teeth 2 of the figure slide to the right.

Assuming a 4 to be showing in the window 4 second from the right, and the control slide to be in normal position, if a 7 is to 30 be added in this column, a colored mark 3 will appear in the hole 6 opposite the number 7, indicating that the stylus is to be moved up instead of down. The stylus is therefore moved up until it strikes the edge 35 of plate 7', which moves the figure slide up three spaces bringing a 1 into the window 4, which, however, will be obscured by the upper end of the control slide until the latter is returned to normal position. By the upward movement of the control slide the number 7 of the lower series will be brought into 40 position just above the edge of plate 7. During the last part of the upward movement of the stylus it will rotate the star 45 wheel o , thereby moving the figure slide 1 to the left down one space so that the figure 1 appears in the window 4. A spring m cooperating with notches j of the guide a insures the movement of the slides for a full 50 space. A transverse bar x is arranged for cooperation with the figure slides to return them to zero position.

The mechanism for adjusting the type 55 wheels has already been described. Adjacent the type wheels is mounted a shiftable carriage 15 having a pad 16 over which is guided a record strip 17. The record strip is fed from a roll 18 and is unwound by a second roll 19. A toothed wheel 20 secured 60 to the roll 19 is adapted to cooperate with a toothed member 22 to rotate the roll 19

for unwinding the record strip. A spring 19 pressed pawl 21 permits rotation of the roll 19 in only one direction. The member 22 is shiftable mounted and is urged by a spring, 65 not shown, into contact with toothed wheel 20. A spring 24 normally holds the carriage away from the type wheels. To print, the carriage is pushed against the type wheels by pressing on flange 25. During the inward 70 movement of the carriage the teeth of wheel 20 slide over teeth 22 which moves down against the action of its spring. On the return movement, the teeth 22 rotate wheel 20 and therewith roll 19, drawing the record 75 strip along to bring another space into printing position. When the individual items have been printed, the final result can be set up on the type wheels for printing by moving the control slides independently in 80 accordance with the figures read from the windows 4.

I claim:

1. In a calculating mechanism having figure slides movable alternatively in either 85 longitudinal direction in carrying out a single kind of calculation, said figure slides being recessed in conformity with the figure arrangement, and means indicating the direction for moving the slides during a calculation, said figure slides being adapted to be actuated by a stylus selectively inserted in said recesses, control slides arranged above said figure slides, said control slides having recesses adapted to register with the recesses 95 of said figure slides, and a plurality of series of figures on said control slides running in the same direction as the figures on the figure slides, and means for returning said control slides to starting position from either 100 longitudinal direction.

2. A calculating mechanism in accordance with claim 1 in which the means for returning the control slides to starting position comprises a pair of transverse bars spaced 105 from the opposite ends of the control slides, and means for moving said transverse bars toward each other.

3. A calculating machine comprising recessed figure slides, indicating devices, recessed control slides adjacent said figure slides and operatively engaging said indicating devices to position said devices as the control slides are moved, the corresponding figure and control slides being adapted to 110 be simultaneously operated by suitable means selectively inserted in recesses in said slides.

The foregoing specification signed at Berlin this second day of October, 1924.

JEAN BERGMANN.
